UNITED STATES PATENT OFFICE.

WILLIAM T. MURPHY, OF NEW YORK, N. Y.

DESIGN FOR A CHANGE PLATE OR TRAY.

SPECIFICATION forming part of Design No. 24,586, dated August 20, 1895.

Application filed June 20, 1895. Serial No. 553,474. Term of patent 3½ years.

To all whom it may concern:

Be it known that I, WILLIAM T. MURPHY, a citizen of the United States, residing at New York city, in the county and State of New York, have invented and produced a new and original Design for a Glass Change Plate or Tray, of which the following is a specification, reference being had to the accompanying drawings, forming a part thereof, in which—

- o Figure 1 is a perspective view of the tray, and Fig. 2 is a longitudinal section through the same.

The design consists in a tray having parallel sides and rounded ends, the top of the

tray being of dish contour, sloping from the 15 sides and the ends, the ends and sides being carried downward, imparting to the body of the tray practically a vertical face.

A further feature of the design consists in round recesses in the under face of the body 20 of the tray.

I claim—

The design for a change plate or tray, substantially as herein shown and described.

WILLIAM T. MURPHY.
